STEREO PHONOGRAPH CARTRIDGE

Jay S. Waxman, Skokie, Ill., assignor to Shure Brothers,
Incorporated, Evanston, Ill., a corporation of Illinois

Application July 7, 1959, Serial No. 56,681

Term of patent 14 years

(Cl. D26—14)

Fig. 1.

Fig. 2.

Fig. 3.

Fig. 4.

Fig. 5

Fig. 6.

Figure 1 is a perspective view of a stereo phonograph cartridge showing my new design;

Figure 2 is a side elevational view, the opposite side being substantially a mirror image thereof;

Figure 3 is a front end elevational view;

Figure 4 is a top plan view;

Figure 5 is a bottom plan view; and

Figure 6 is a rear end elevational view thereof.

I claim:
The ornamental design for a stereo phonograph cartridge, substantially as shown and described.
